(57) **CLAIM**

The ornamental design for a compute box, as shown and described.

DESCRIPTION

FIG. 1 is a top-perspective view according to a First Embodiment of our design;

FIG. 2 is a bottom-perspective view thereof;

FIG. 3 is a top plan view thereof;

FIG. 4 is a bottom plan view thereof;

FIG. 5 is a left-side view thereof;

FIG. 6 is a right-side view thereof;

FIG. 7 is a front view thereof;

FIG. 8 is a rear view thereof;

FIG. 9 is a top-perspective view according to a Second Embodiment of our design;

FIG. 10 is a bottom-perspective view thereof;

FIG. 11 is a top plan view thereof;

FIG. 12 is a bottom plan view thereof;

FIG. 13 is a left-side view thereof;

FIG. 14 is a right-side view thereof;

FIG. 15 is a front view thereof; and,

FIG. 16 is a rear view thereof.

Conventional shading is illustrated throughout the line drawings, but forms no part of the claimed design.

The broken lines show portions of the compute box that form no part of the claimed design.

1 Claim, 12 Drawing Sheets
